(57) CLAIM

The ornamental design for tobacco bowl holder, as shown and described.

DESCRIPTION

FIG. 1 is a perspective view of a tobacco bowl holder design; FIG. 2 is a top view thereof; FIG. 3 is a side view thereof; FIG. 4 is a bottom view thereof; and, FIG. 5 is an expanded view as shown in FIG. 2.

The broken lines consisting of evenly spaced dash lines in the drawing depict portions of the tobacco bowl holder that forms no part of the claimed design; The broken lines consisting of short and long dash broken lines are for purposes of annotating the enlarged view only and form no part of the claimed design; The zig zag break lines shown in the drawings, indicate a symbolic break in length. The appearance of any portion of the article between the break lines, forms no part of the claimed design.
